RING

Ronald A. Thompson, 7 Glazebrook Ave., Suite 5,
Toronto, Ontario, Canada

Filed Feb. 22, 1971, Ser. No. 117,883

Term of patent 14 years

Int. Cl. D11—01

U.S. Cl. D45—10

FIG. 1

FIG. 2

FIG. 3

FIG. 4

FIG. 5

FIG. 6

FIG. 7

FIG.8

FIG.9

FIG.10

FIG.11

FIG.13

FIG.12

FIG.14

FIGS. 1 and 2 are front and rear perspective views respectively of a ring showing my design;

FIG. 3 is a front elevation of the ring shown in FIGS. 1 and 2;

FIGS. 4 and 5 are end elevations of the ring shown in FIGS. 1 and 2;

FIG. 6 is a rear elevation of the ring shown in FIGS. 1 and 2;

FIG. 7 is a top plan of the ring shown in FIGS. 1 and 2;

FIG. 8 is a front perspective view of another embodiment of the ring shown in FIG. 1 having a bevel cut gem on the top thereof;

FIG. 9 is a rear perspective view thereof;

FIG. 10 is a front elevation of the ring shown in FIGS. 8 and 9;

FIGS. 11 and 12 are end elevations of the ring shown in FIGS. 8 and 9;

FIG. 13 is a rear elevation of the ring shown in FIGS. 8 and 9;

FIG. 14 is a top plan of the ring shown in FIGS. 8 and 9;

FIG. 15 is a front perspective view of a further embodiment of the ring shown in FIG. 1 having gems set within the outline of a numeral one at the top thereof;

FIG. 16 is a rear perspective view thereof;

FIG. 17 is a front elevation of the ring shown in FIGS. 15 and 16;

FIGS. 18 and 19 are end elevations of the ring shown in FIGS. 15 and 16;

FIG. 20 is a rear elevation of the ring shown in FIGS. 15 and 16; and

FIG. 21 is a top plan of the ring shown in FIGS. 15 and 16.

I claim:

The ornamental design for a ring, as shown and described.
